CASTING MOLD

Alexander Ashton Marks, Uniontown, and John D. Augustine, South Uniontown, Pa.; said Augustine assignor to Richmond Radiator Company, Inc., Uniontown, Pa., a corporation of Delaware

Application December 18, 1939, Serial No. 309,810

8 Claims. (Cl. 22—131)

Our invention is an improved casting mold. Our improvements are designed primarily to permit the casting integrally of relatively large castings having adjacent substantially parallel body members of considerable extent connected together by elements of relatively small cross section extending transversely to and formed integrally with the body members, and to thereby avoid the usual expense of machining and coupling such members.

Our improvements are further designed to improve the distribution and solidification of the metal or other casting liquid in the mold and the venting of gases from the mold in making such castings so that no part of the mold is subjected to excessive pressure from the casting metal, the formation of blow holes is minimized, and the waste pieces formed in the sprue holes, gates and runners are readily separated from the casting.

Our improvements are further designed to provide a multi-part mold containing a series of superposed casting spaces each containing a core having end members firmly securing the core body against movement in any direction and containing runners connecting the casting spaces with their respective gates.

Our improvements are particularly adapted for use in the manufacture of integral castings having a plurality of rows of hollow tubes with their ends integrally connected by header elements such, for instance, as the tubular heat exchangers with integral headers shown in the application of A. A. Marks, Serial No. 267,745, filed April 14, 1939. A further example of the type of work for which our invention is particularly designed is the casting, as an integral unit, of all the radiator sections required to make a complete radiator having an enclosing shell of the general character shown in Letters Patent No. 2,083,028 of June 8, 1937.

Our invention permits the use of a single pattern to provide all the mold sections required for the making of an integral casting composed of any desired number of tubes in a row and any desired number of rows. Such pattern may be used sequentially as the top plate for a series of boxes during the compaction therein of core sand containing a suitable binder; the core sand being supported during compaction and subsequent baking by a flat bottom plate for each box. Where, however, it is desired that the end sections of the casting differ from the intermediate sections thereof, one pattern is used for making

the cope and drag mold-parts and another pattern is used for making the cheek mold-parts.

Each mold section has a flat face and an intaglio face and all the intaglio faces contain 5 similar impressions. Each impression preferably forms a horizontal concave casting space, vertical casting spaces normal to the plane of the horizontal casting space, prints adjacent to the vertical casting spaces for receiving core end members, channels connecting the casting spaces with individual horizontal gates, and vertical holes at the ends of the gates and which serve both as molten metal inlets and as gas vents. The vertical casting spaces, prints and vertical 10 holes in superposed mold sections register and communicate with one another respectively.

The cope and drag mold sections differ from the cheek mold sections in thickness and in depth of the vertical casting spaces and provide 15 a closed top and bottom for the top and bottom vertical casting spaces and a closed bottom for the vertical holes. The top of each vertical hole in the cope mold section may be surrounded by a runner box of core sand.

20 Between the intaglio faces of each pair of mold sections there is housed a baked core so molded of sand mixed with a binder that its horizontal body partly fills the horizontal casting space and its ends fit into the prints of such mold sections. 25 The mold sections and cores are relatively porous and the latter preferably contain internal passages facilitating the venting of gases, which may escape through the mold, through the vertical holes and from between the mold sections. 30 The formation of blow holes in the casting due to internal pressure from gases is thereby eliminated or minimized.

35 A suitable number of the baked mold sections and cores are superimposed upon one another so that their vertical holes at the ends of the gates register and their vertical casting spaces register. The gates, runner, channels, and outlines of the impressions in intaglio faces of adjacent mold sections coincide with one another, 40 and a core is housed in each casting space so formed. Sometimes openings are formed from a horizontal casting space through the flat face of a mold section, and in such case imperforate sections of the flat face of an adjacent mold section cover such openings.

45 The end members of the core disposed between and spaced from the intaglio faces of each pair of sections partially fill the prints or slots of the pair of mold sections between which the body of such core lies. The walls of these end members

so abut the walls of the slots as to prevent movement of the core in its casting space in any direction. End members of superimposed cores preferably abut one another and contain grooves forming core runners connecting the mold runners with the vertical casting spaces. The inner faces of core end sections are spaced from the inner faces of the vertical casting spaces and form a face for molding and giving form to the outer surface of casting members connecting tubes formed around the core bodies.

The impression in the intaglio face of each mold section may be symmetrical or asymmetrical with respect to the longitudinal center line thereof, but the vertical holes at the ends of the gates and the through slots formed by the vertical casting spaces and adjacent prints are symmetrical with respect to such center line and are also symmetrically arranged with respect to the transverse center line of the mold sections.

When the impressions are asymmetrical, the mold sections are preferably assembled so that the bulk of the casting space formed by the impressions of one pair of sections lies on one side of the longitudinal center line and the bulk of the casting space formed by the impressions of the next pair of sections lies on the opposite side of the longitudinal center line. Such transposition is effected by turning the mold sections of the second pair end for end with respect to the mold sections of the first pair.

The vertical casting spaces and prints in the drag and cope mold sections of the series do not extend completely through such sections and the wall areas at the ends thereof respectively mold surfaces complementary to the impressions in such mold sections for molding the ends of the castings.

By our improvements a tubular casting of any desired length and free from blow holes may be made from a series of similar mold sections and cores of simple construction. The pattern work and core work required in making the mold are simplified and reduced to a minimum. Several different types of castings may be made from the same pattern by changing the positions of consecutive pairs of mold sections made therefrom relatively to one another, as, for instance, by placing the head of the impression in one pair of sections adjacent to the foot of the impression in an adjacent pair of mold sections.

The characteristic features and advantages of our improvements will further appear from the following description and the accompanying drawings in illustration thereof.

In the drawings, Fig. 1 is a perspective view of a flask containing mold sections built up in accordance with our invention; Fig. 2 is a broken transverse sectional view of the flask and mold taken on the line 2—2 of Fig. 1 and showing a casting therein; Fig. 3 is a perspective view of the cope of the flask of Figs. 1 and 2 and of the cope mold section therein; Fig. 4 is a perspective view showing a core suitable for use in conjunction with the cope mold section or drag mold section; Fig. 5 is a perspective view of a flask cheek section with an intermediate mold section therein; Fig. 6 is a perspective view of an inverted flask cheek section with an intermediate mold section therein; Fig. 7 is a perspective view of a core suitable for use between the intaglio faces of intermediate mold sections; Fig. 8 is a perspective view of a second flask cheek section with an intermediate mold section therein, and is similar to Fig. 5 but viewed from a slightly

different angle; Fig. 9 is a perspective view of a further flask cheek section with an intermediate mold section therein, and is similar to Fig. 6 but viewed from a slightly different angle; Fig. 10 is a perspective view of an inverted core similar to the core shown in Fig. 4 and adapted for use in conjunction with a cope mold section or drag mold section; Fig. 11 is a perspective view of the flask drag section with a bottom mold section therein; Fig. 12 is an irregular horizontal sectional view through a flask, mold and casting, including wastage metal, taken on the line 12—12 of Fig. 13; and Fig. 13 is an irregular longitudinal vertical sectional view through a flask, mold and casting, including wastage metal, taken on the line 13—13 of Fig. 12; hatching, stippling and mold and core division lines being omitted from Figs. 12 and 13 for the sake of clearness.

The flask sections and the mold sections shown in Figs. 3 and 11 are identical with one another excepting that the vertical holes at the ends of the gates extend entirely through the mold section of Fig. 3 and are surrounded by casting boxes. The cores shown in Figs. 4 and 10 are identical and the core shown in Fig. 7 differs therefrom only in the extent of the channels in the end members forming core runners. The flask cheek sections and intermediate mold sections shown in Figs. 5, 6, 8 and 9 are identical with one another and differ from the flask and mold sections shown in Figs. 3 and 11 only in thickness and the results of the differences in thickness.

In the embodiment of our invention illustrated in the drawings, a flask, composed of the drag 1, cheeks 2, and cope 3, contains a multi-part mold composed of the bottom mold section 4, intermediate mold sections 5, top section 6, and cores 7 and 7'. While the flask members are necessary for the molding and baking of the mold parts, the respective flask members may be composed of hinged or detachable members to permit the removal of the flask from the mold before casting.

In making the mold sections 4, 5 and 6, the flask members 1, 2 and 3 may be placed upon flat plates and each flask member is covered by a pattern. The same pattern may be used consecutively with all the flask sections 2 and in some instances the same pattern may be also used with the flask sections 1 and 3. Where, however, the ends of the casting are to be provided with flanges or other members differing in width or character from the members between the intermediate casting sections, it is preferable to use a separate pattern with the flask sections 1 and 3. In the present instance, the pattern used with the flask members 1 and 3 forms vertical casting spaces in the mold sections 4 and 6 deeper than the corresponding vertical casting spaces in the sections 5 and such pattern is provided with detachable extensions for completely penetrating the cope section to form vertical holes at the ends of the cope gates.

Core sand is compacted in the flask members around the patterns in any suitable manner, and when the pattern is removed from each flask member there is left in the sand therein a complete imprint of the pattern. The thickness of the mold section 4 is sufficient to provide a continuous bottom for the mold and the thickness of the cope section 6 is sufficient to form a mold cover which is continuous excepting for the sprue holes and riser holes therein.

As shown in the drawings, each of the mold sections 4, 5 and 6 formed as above described

has a flat face on one side and an intaglio face on its other side.

The intaglio face of each mold section 4, 5 or 6 includes an impression 8 for molding an exterior face of the tubular portion of a casting; parting faces such as 9, 9', 9'' and 10 for contacting similar faces of an adjacent section; shallow grooves 11 to form mold runners, and deeper grooves 12 to form gates.

Each intermediate mold section 5 contains through slots forming vertical casting spaces 14 and prints 15 adjacent thereto. The mold sections 4 and 6 each contain slots passing only partly therethrough and similar in general outline and in relative positions to, but of greater depth than, the slots in the mold sections 5. The slots in the sections 4 and 6 provide vertical casting spaces 14a communicating with the vertical casting spaces 14 and also provide prints 15a adapted to register with prints 15.

Each intermediate mold section 5 contains vertical through holes 16 at the ends of the gate grooves 12 thereof. The top mold section 6 has vertical holes 16a passing therethrough and aligned with the holes 16, and the mold section 4 has vertical holes 16b passing only partly therethrough and aligned with the holes 16. The upper ends of the holes 16a are surrounded by runner boxes 17.

In the example shown, each impression 8 for molding an outer surface of a tubular portion of a casting, consists of parallel troughs 18 and 18'. Depressions 19 and 19' extend along the upper edges of the troughs 18 and 18'.

The walls of each trough contain staggered transverse grooves 20 and 20' the apexes of which may form openings in the flat faces of the intermediate mold sections 5 but do not penetrate through the thicker mold sections 4 and 6. The openings formed by the slots 20 and 20' in one intermediate mold section are covered by an imperforate portion of the flat face of an adjacent mold section.

The troughs 18 and 18' have similar tapering ends 18a merging into the inner faces of the vertical casting spaces 14 of the sections 5 or 14a of the sections 4 and 6.

The cores 7 and 7' comprise end members 21 connected by spaced similar cross-bars 22, each of substantially rhomboidal cross-section. The cross-bars and end members may contain internal passages 7a to facilitate escape of gases generated within the cores from the binder mixed with the core sand. The respective cross-bars have tapering ends 22a, and the contours of the cross-bars 22 and their ends 22a are complementary to the contours of the troughs 18 and 18' and their tapering ends 18a. Each cross-bar 22 has a similar top and bottom face, and contains sinuous grooves 26 and 27 along the longitudinal ridges thereof.

The core 7, complementary to the section 4, has runner grooves 28 in the upper surfaces of its end members 21 and runner grooves 29 extending part way along the end surfaces of the member 21 and communicating with the grooves 28. The core 7 used in conjunction with the section 6 is inverted so that its runners 28 are in the bottom faces of its end members 21 and its runner grooves 29 extend only part way up the end faces of the members 21. The cores 7' which are used in conjunction with two mold sections 5 have runner channels 28a and 28a' in the upper and lower surfaces of the member 21 and have runner grooves 29a extending the

full height of the end members 21 and communicating with the runner grooves 28a and 28a'. In both the cores 7 and 7' the inner faces of the end members 21 are devoid of runner grooves.

When a mold for casting is to be made, a core 7 is placed in the bottom mold section 4 with the outer faces of the core end members 21 engaging the outer faces of the prints 15a and the side faces of the end members 21 engaging the side faces of the slots 15a, and with the core runners 29 and 28 registering with the mold runners 11. To avoid excessive strains on the end members 21 and their frictional engagement with the print walls, the bottom faces of the bars 22 may be spaced from the upper faces of the troughs 18 and 18' by suitable chaplets.

An intermediate mold member 5 is laid on top of the member 4 so that the parting faces of the two members contact and the imprint in the member 5 registers with the imprint in the member 4 so as to form gates by the registration of the gate grooves 12, to form runners by the registration of the runner grooves 11, to form a casting space for transverse elements by registration of the vertical casting spaces 14a and 14, and to form a horizontal casting space around the core 1.

A further intermediate mold section 5 is laid with its flat face on the flat face of the first mold section 5, a core 7' is laid in the second mold section 5, and a further mold section 5 is laid with its intaglio face in juxtaposition to the intaglio face of the second laid mold section 5, the bars of the second core section 7' being housed within the casting spaces thus formed.

The second pair of mold sections may be laid with their casting spaces vertically aligned with the casting spaces of the first pair of mold sections, but preferably the second pair of mold sections are turned end for end with respect to the first pair of mold sections so that the casting spaces of the second pair of mold sections are offset relatively to the casting spaces of the first pair of mold sections, as shown in Fig. 2.

Further pairs of mold sections 5 and cores 7' may be laid to any desired height to form a casting containing any desired number of tubes.

The top of the stack of mold sections is formed by placing an inverted core 7 above the last intermediate section 5 and covering it with the cope 6 with its intaglio face in registration with the intaglio face of such mold section 5.

The several mold sections may be accurately aligned by aligning the apertures 30 in the lugs 55 on the flask parts so that the vertical holes at the ends of the gates are all vertically aligned with the pouring tubes on the top of the cope.

Preferably metal is simultaneously poured in diagonally positioned sprue holes. As the metal rises in the sprue holes, it first flows into the gates formed by the grooves 11 in the bottom pair of mold parts 4 and 5, thence flows through the mold runners and core runners into the vertical casting spaces 14a and 14 and thence into the casting space surrounding the bottom core 7. When this is filled, the rising of the metal in the sprue holes causes it to flow into the gate formed by the grooves 12 in the next pair of mold sections 5, thence through the corresponding runners into the vertical casting spaces of the second pair of mold sections, and thence into the casting space surrounding the second core 7. The metal in the vertical casting spaces formed by the superposed mold sections forms elements continuous with one another and integrally united

with the metal in the casting spaces surrounding the cores 7, so that there is formed a series of tubes having flaring ends united by transverse elements forming headers integral therewith.

It will be understood that the troughs 18 and 18' forming the main casting space, mold the outer surfaces of the bodies of tubes of the casting; that the transverse grooves in the walls 20 and 20' of the troughs mold staggered transverse baffles integrally on the outer walls of the tube bodies; that the depressions 19 and 19' form longitudinal fins on the front and rear edges of the tube bodies; that the tapering ends 18a mold the outer surfaces of the flaring ends of the tubes; that the metal solidifying in the vertical casting spaces has its outer surface molded by the inner surfaces of the members 21 and its inner surface molded by the inner surfaces of the slots 14 and 14a to form continuous integral headers connecting the tube ends with one another; that the bars 22 mold the inner surfaces of the tubes; and that the grooves 26 and 27 mold sinuous baffles integrally on the inner surfaces of the tubes.

The gases evolved from the disintegration of the binder contained in the core 7 escapes through the ends of the tubes, and through the runners, gates and riser holes that are not being used for pouring, as well as through the porous structure of the mold and between the members thereof.

Having described our invention, we claim:

1. A mold for casting, comprising top, bottom and intermediate mold sections having partings between them and arranged in complementary pairs, each of said mold sections containing a shallow concavity with parting faces beside it and each of said intermediate mold sections having a substantially flat parting face on the opposite side thereof from its hollow concavity, and through passages through which said hollow concavities communicate with the partings between flat parting surfaces aforesaid.

2. A mold for casting comprising a plurality of mold sections arranged in pairs, each pair having juxtaposed faces containing imprints forming complementary shallow concavities and slots extending transversely to the faces of said sections and of greater depths than said concavities, and a core having a body extending the length of said complementary concavities and having enlarged ends bearing against the outer walls and spaced from the inner walls of said slots to prevent longitudinal shifting of said core and provide casting spaces transverse to the casting spaces formed by said concavities and core.

3. A mold for casting comprising mold sections containing complementary shallow concavities and slots transverse to the plane thereof, of a

core seated in said concavities and having enlarged ends seated in said slots, said ends containing spaced channels in the tops, bottoms and outer faces thereof.

5 4. A mold for casting comprising mold sections each containing an imprint forming a longitudinal shallow concavity, through slots adjacent to the ends of said concavity, gate grooves substantially parallel with such slots but extending only partly through the section, runners connecting said gate grooves and through slots, and through holes at the ends of said gate grooves; and a core complementary to said concavity and through slots.

15 5. A mold for casting comprising mold sections each having a substantially flat face and an opposite face containing an imprint forming a longitudinal hollow concavity and slots spaced along said concavity transversely thereto and open through the flat face of said section.

25 6. A mold for casting comprising a plurality of mold sections each containing an imprint forming a pair of parallel shallow concavities, a through slot extending across substantially the entire width of both said concavities, a gate groove parallel to and of lesser depth than said slot and spaced therefrom by a ridge, runners in the top of said ridge, and a through hole at an end of said gate groove; and a core comprising spaced bars connected by an end member in said concavities and slot; said end member containing runners complementary to the runners in said ridge.

30 7. A mold comprising mold sections arranged in complementary pairs, each pair having juxtaposed faces each containing an imprint forming a longitudinal shallow concavity and a through slot extending transversely to the concavity; and a core for each pair of complementary sections, each core having an end member seated in the through slots of its pair to maintain the registration thereof and superposed cores forming between them runners communicating with the concavities below and above such runners.

45 8. A mold for casting comprising a plurality of mold sections forming complementary pairs; the sections of each pair containing complementary longitudinal shallow concavities disposed asymmetrically of the longitudinal center line of its section and containing through slots transverse to said concavities at the ends thereof, such slots each being symmetrical with respect to the longitudinal center line of its section; said pairs being disposed with the through slots all in registration throughout their lengths and with the concavities of one pair offset laterally with respect to the concavities of another pair.

ALEXANDER ASHTON MARKS.
